US0D1104655S

(12) **United States Design Patent** (10) **Patent No.:** **US D1,104,655 S**
(45) **Date of Patent:** **** Dec. 9, 2025**

(54) **POPCORN BUCKET**

(71) Applicant: **Guangdong Engelhardt-Meitu Rubber & Plastic Technology Co., Ltd,**
Zhongshan (CN)

(72) Inventor: **Wenhui Zhou**, Zhongshan (CN)

(73) Assignee: **Guangdong Engelhardt-Meitu Rubber & Plastic Technology Co., Ltd,**
Zhongshan (CN)

(**) Term: **15 Years**

(21) Appl. No.: **29/943,111**

(22) Filed: **May 20, 2024**

(30) **Foreign Application Priority Data**

Nov. 29, 2023 (CN) 202330783902.7

(57) **CLAIM**

The ornamental design for a popcorn bucket, as shown and described.

DESCRIPTION

FIG. 1 is a perspective view of a popcorn bucket, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a cross-sectional view of portion of FIG. 8 thereof. The dot-dash broken lines depict the boundaries of the enlargements that form no part of the claimed design.

The broken lines shown in the drawings illustrate portions of the popcorn bucket that form no part of the claimed design.

1 Claim, 9 Drawing Sheets
